UNITED STATES PATENT OFFICE.

JAFEW S. VAN BUREN, OF ALBANY, NEW YORK.

DESIGN FOR A STOVE.

SPECIFICATION forming part of Design No. 34,950, dated August 13, 1901.

Application filed July 3, 1901. Serial No. 67,039. Term of patent 7 years.

To all whom it may concern:

Be it known that I, JAFEW S. VAN BUREN, a citizen of the United States of America, and a resident of the city and county of Albany, State of New York, have invented and produced a certain new and original Design for Stoves, of which the following is a specification.

My invention relates to a design for stoves; and the object of my invention is to provide a new and useful design for cooking-stoves or ranges, of which the following is a specification, reference being had to the accompanying drawing, forming a part thereof.

The figure is a perspective view showing my new design.

As shown in the drawing, the leading or material feature of my design consists of a

series of projecting convolutions A, arranged in such a manner that each convolution is 20 provided with a stem a, inclosing a wider curved portion b, disposed or arranged as shown in the figure. I arrange a central portion plain, as shown at F.

Having described my invention, what I 25 claim as new, and desire to secure by Letters Patent, is—

The design for a stove, as herein shown and described.

Signed by me at Albany, New York, this 30 22d day of June, 1901.

JAFEW S. VAN BUREN.
